(57) **CLAIM**

The ornamental design for a high torque tool, as shown and described.

DESCRIPTION

FIG. 1 is a perspective view of the high torque tool, from an upper perspective;

FIG. 2 is a perspective view of the high torque tool, from a lower perspective;

FIG. 3 is a side elevation view of the high torque tool;

FIG. 4 is a bottom view of the high torque tool;

FIG. 5 is a top plan view of the high torque tool; and

FIG. 6 is rear elevation view of the high torque tool; and, FIG. 7 is a front elevation view of the high torque tool, 180 degrees offset from FIG. 6.

The dot-dot-dash broken lines adjacent to the shaded area represents an unclaimed boundary of the claimed design. The remainder of the broken lines are provided for environmental purposes only and form no part of the claimed design.
